ATTORNEY

UNITED STATES PATENT OFFICE.

HORACE P. BROWN, OF OAKLAND, CALIFORNIA, ASSIGNOR TO PACIFIC-BURT COMPANY, LIMITED, OF TORONTO, ONTARIO, CANADA, A CORPORATION OF ONTARIO.

SALES-BOOK.

1,287,866.

Specification of Letters Patent. Patented Dec. 17, 1918.

Application filed March 21, 1917. Serial No. 156,274.

To all whom it may concern:

Be it known that I, HORACE P. BROWN, a citizen of the United States, residing at Oakland, in the county of Alameda and 5 State of California, have invented certain new and useful Improvements in Sales-Books, of which the following is a full, clear, and exact description, such as will enable others skilled in the art to which it 10 appertains to make and use the same.

This invention relates to manifolding devices, and with regard to its more specific features, to a manifolding salesbook.

An object of this invention is to provide 15 a practical book in which a multiple record may be made.

Another object of the invention is to provide a device of the character described in which all of the records may be strong and 20 legible.

Another object is to provide a device of the character described in which all the records will be direct reading.

Other objects will be in part obvious and 25 in part pointed out hereinafter.

The invention accordingly consists in the features of construction, combinations of elements and arrangement of parts which will be exemplified in the construction here- 30 inafter set forth, and the scope of the application of which will be indicated in the following claims.

In the accompanying drawing forming part of this specification, and wherein 35 similar reference characters refer to similar parts throughout the several views,—

Figure 1 is a perspective view of an embodiment of the invention; and

Fig. 2 is a side view showing the leaf ar- 40 rangement.

Referring now more specifically to the drawing, the numeral 1 indicates a back, to one end of which is attached a support 2, as by staple 3, the support 2 being somewhat 45 shorter than the back. To the other end of the back 1 is attached the pad 4 comprising a series of leaves bound together, and also, if desired, to the back 1 by staple 5. To the other end of the support 2 from the 50 staple 3 is attached a pad 6 comprising a series of sheets bound together, and also, if desired, to the support 2 by staple 7. Each of the sheets of the pad 6 is folded upon itself in a zigzag manner to form three super- 55 posed leaves, as a bound leaf 8 and inter-

mediate leaf 9 and upper leaf 10, operatively associated with the pad 6. In position to be inserted between leaves 8 and 9 of the top sheet is a carbon sheet 11, which may be conveniently bound inwardly with the pad 6. The pad 6 and the pad 4 and the carbon sheet 11 are so disposed relative to each other that the bottom sheets in the pad 4 may be inserted between the leaf 9 and the carbon sheet 11. For the purpose of trans- 60 ferring any record made upon the leaf 10, to the upper side of the leaf 9 and to the upper side of the sheet 12 from the pad 4, suitable transfer material will be placed between the leaves 9 and 10 and between 70 the leaf 9 and sheet 12. This may be conveniently done by carbonizing the under surface of leaves 9 and 10.

The manipulation of the device is as fol- 75 lows: The leaves of the pad 4 having been folded back to expose the pad 6, the leaves 9 and 10 of the top sheet from the pad 2 may be folded back to permit the carbon 11 to fall upon the leaf 8. The bottom sheet from the pad 4 may now be superposed on 80 the carbon and the sheets 9 and 10 folded back into place. Any record which is now made upon the sheet 10 will be transferred to the leaves 8, 12 and 9 and will read direct upon the upper side of each sheet. The 85 sheets 8, 9 and 10 may now be removed from the book and the sheet 12 may be placed between the support 1 and 2, leaving the book in position for a repetition of the above manipulation.

By the above construction it will be evi- 90 dent that not only can a four copy record be made, of which one copy may remain in the book, but also that all four copies will be clear and legible because of the fact that 95 the fourth copy, which receives the least pressure from the pencil as the record is made, receives the impression from a carbon sheet which gives a much stronger impres- 100 sion where the record is made from the car- bonized under face of a record sheet.

Thus by the above described construction are accomplished, among others, the objects hereinbefore set forth.

As many changes could be made in the 105 above construction and many apparently widely different embodiments of this invention could be made without departing from the scope thereof, it is intended that all matter contained in the above description or 110

shown in the accompanying drawing shall be interpreted as illustrative and not in a limiting sense.

It is also to be understood that the language used in the following claims is intended to cover all of the generic and specific features of the invention herein described and all statements of the scope of the invention, which, as a matter of language, 10 might be said to fall therebetween.

Having described my invention, what I claim as new and desire to secure by Letters Patent is:

1. A device of the character described comprising, in combination, a pad having its sheets folded back upon itself to form three superposed leaves, a second pad supported in such relation to the first pad that its sheets may be interposed between two of 20 the leaves of each sheet of the first pad, successively, transfer material upon the under side of the top two leaves of each sheet of the first pad, and a sheet of transfer material carbonized on its lower side between the 25 lower leaf of the sheet of the first pad and the interposed sheet.

2. A device of the character described comprising, in combination, a support, a pad of leaves attached to one end of said support so as normally to overlie the same, a second pad of leaves comprising sheets each folded upon itself to form three superposed leaves, said pad being connected to said support and adapted to overlie the same with 35 its bound edge farther from the end of the support than the bound edge of the first pad, whereby the sheets of the first pad may be interposed between the leaves of a sheet of the second pad to form a quadruplicate 40 record, and transfer material adapted to transfer to the lower three sheets of said record the impression made upon the upper.

3. A device of the character described comprising, in combination, a support, a pad of leaves attached to one end of said support so as normally to overlie the same, a second pad of leaves comprising sheets each folded upon itself to form three superposed leaves, said pad being connected to said support and 45 adapted to overlie the same with the bound edge farther from the end of the support than the bound edge of the first pad, whereby the sheets of the first pad may be interposed between the leaves of a sheet of the 50 second pad to form a quadruplicate record, transfer material on one face of two of the leaves of each of the sheets of the second pad, and a sheet of transfer material adapted to be disposed between the lower leaf of 55 the top sheet and the remaining leaves thereof.

4. A device of the character described comprising, in combination, a back, a pad of leaves attached to one end of said back, a support, a pad of leaves attached to one end of the support, comprising sheets each folded upon itself to form three superposed leaves, the support and the back attached together at their other ends with the first pad and the end of the back extending out 65 from under the support whereby a pocket is formed between the support and the back, and the leaves of the first pad may be inserted between the leaves of a sheet of the second pad to form a quadruplicate record, 70 and transfer material attached to transfer to the lower three sheets of said record the impression made upon the upper.

5. A device of the character described comprising, in combination, a back, a pad of leaves attached to one end of said back, a support, a pad of leaves attached to one end of the support, comprising sheets each folded upon itself to form three superposed leaves, the support and the back attached 85 together at their other ends with the first pad and the end of the back extending out from under the support whereby a pocket is formed between the support and the back, and the leaves of the first pad may be inserted between the leaves of a sheet of the second pad to form a quadruplicate record, 90 transfer material on one face of two of the leaves of each of the sheets of the second pad, and a sheet of transfer material adapted to be disposed between the lower leaf of the top sheet and the remaining leaves thereof.

6. A device of the character described comprising, in combination, a plurality of pads, a back to which each pad is secured, one of said pads being secured to said back by a pad support connected to said back at the end opposite the bound end of the leaves of the last mentioned pad, the other pad being secured to the back so that the leaves thereof are adapted to underlie and overlie the other pad, the pad which is connected to said back by said support comprising sheets each folded upon itself to form three superposed leaves, the upper two of which have transfer material on their under faces, and a carbon sheet secured to the back and adapted to lie against the lower leaf of said folded sheet to transfer impressions thereto.

In testimony whereof I affix my signature, in the presence of two witnesses.
